UNITED STATES PATENT OFFICE.

LEO KNIGOFF, OF NEW YORK, N. Y.

RADIO DIAL.

Application filed October 18, 1926. Serial No. 142,490.

This invention relates to radio station selecting dials and in particular to one embodying therein a counterweight.

A particular object of the invention is to provide a station selecting dial having incorporated therein a suitable counterweight which will counterbalance the weight of the movable condenser plates which are carried on the shaft to the end of which the selecting dial is secured.

A further object of the invention is to provide a simplified method of attaching to the dial, a counterweight of any desired dimension and weight which can be suitably positioned within the dial to counterbalance, as before described, the weight of the movable blades of the condenser.

A further particular object of the invention is to provide in combination with either a solid type dial or hollow dial, a counterweight of various configurations and weights so that the movable condenser plates will be balanced and the manipulation thereof, through the medium of the operating dial, will be more readily facilitated.

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views of which,

Figure 1 is a fragmentary view in side elevation of a condenser and radio receiving set panel, the shaft of the condenser having provided thereon my improved radio dial which is shown in section to disclose on the interior thereof, the counterweight.

Figure 2 is a front view in elevation of the counterweighted dial, as seen in Figure 1.

Figure 3 is a view in perspective of the counterweight itself, a portion thereof being broken away to show how the same is attached to the interior of the dial.

Figure 4 is a modified form illustrated as a face view in which is incorporated within the dial, a counterweight of different shape and dimension, the dial itself having a solid finger gripping portion, and

Figure 5 is a view in perspective of the counterweight particularly suited for use with the solid dial, illustrated in Figure 4.

Referring to the drawings in detail 5 indicates a condenser of the standard type, the

fixed plates of which are indicated as at 6 and the movable ones by the numeral 7, the latter being secured in the usual manner to the rotor shaft 8, which extends through the radio receiving set panel 9 and has secured at its outer end the dial 10. This dial, after the usual order, is marked on its peripheral edge, as at 11, with suitable indicating marks as used in connection with radio receiving apparatus.

In order to adjust the condenser to tune the set into resonance with the wave length of a particular broadcasting station, the dial is revolved in the well known manner and thereby causes rotation of the movable element 7 of the condenser 5 as is well known.

In the radio art, various features have been incorporated in the different parts to eliminate friction and to counterbalance the rotation parts so that easy manipulation of the tuning parts may be accomplished and to this end, I provide an improved dial 10 of hollow construction, the material used being bakelite, hard rubber or other suitable substance and the dial being cast to provide the obliquely disposed scale bearing portion 12 which is formed at the edge of the base 13 concentrically with which is cast the upstanding finger gripping portion or knob 14, the peripheral face of which is usually, although not always, fluted or scored to provide a firmer grip for the fingers in rotating the dial.

In order to counterbalance the weight of the moving plate 7 of the condenser 5, it is necessary to provide in the dial 10, a suitable counterweight 15, and in the hollow, knob portion 14, I have provided a plurality of cast sleeves 16, which extend inwardly from the face of the knob portion 14 and are threaded interiorly to receive the holding screws 17. These holding screws pass through suitable openings 18 in the counterweight 15 and may be arranged according to the shape of the counterweight. In this instance, I have provided a projected end 19 on the counterweight and an enlarged, opposite portion 20, the center thereof being pierced with a bore 21 into which extends the rotor shaft 8, which carries the movable condenser element 7. Longitudinally of the counterweight 15 and extending upwardly from the bottom thereof, in the enlarged portion 20, I provide a threaded bore 22,

when the counterweight 15 is in place, this bore matching with an opening 23 in the

finger knob surface 14 and through which is threaded, a set screw 24. This set screw not only acts to secure the counterweight in position within the dial, but also connects the dial itself with the end of the rotor shaft 8.

It is evident that the counterweight may be of metal or other suitable, heavy material, and may be cast in the particular shape or design desired to carry out the counterbalancing feature of my invention, and it is evident that any number of screws 17 may be used to attach the counterweight in position within the knob 14 of the dial.

In referring to Figures 4 and 5, I have shown a dial which is cast with a solid knob portion 25 in connection with which is incorporated, a counterbalancing weight 26, which fits within a suitable depression formed in the knob 25 when the same is cast, the depression being arranged to receive the counterweight 26 which is secured in position through the medium of the screws 27 which are passed through the counterweight 26 and are secured in the body of the dial much in the same manner as that outlined in Figure 2. The counterweight itself is arranged to encompass the end of the shaft 8, if desired, or being provided with a bearing so that it rests beneath the shaft 8, the counterweight itself being provided with the usual set screw 28 which retains the dial in connection with the end of the shaft 8, as heretofore described.

It will be evident, therefore, that I have provided an improved counterweighted dial, which will render the operation of the movable condenser plate more easy and will also tend to maintain them securely in the position to which they are revolved, as it has often been the case, that the weight of the plate, when turned to an angular position, due to vibration of the set, or outside vibration, gradually turn from their position and destroy the tune of the set.

While I have illustrated and described my

invention with some degree of particularity, I realize that in practice various alterations therein may be made. I therefore reserve the right and privilege of changing the form of the details of construction or otherwise 50 altering the arrangement of the correlated parts without departing from the spirit of the invention or the scope of the appended claims.

Having thus described my invention, what 55 I claim as new, and desire to secure by United States Letters Patent is:—

1. The combination with a condenser having a plurality of movable plate members and an operating shaft, of a dial, for indicating the position of the plate members, a counterweight arranged in said dial, means for fastening the counterweight in the dial and said counterweight providing a bearing 60 for said shaft.

2. The combination with a condenser having a plurality of movable plates and a shaft for operating said plates, of a dial, the dial being cast to provide an extended finger knob portion, a counterweight in said knob, and means extending through the knob and counterweight for securing the dial to the condenser shaft.

3. The combination with a condenser shaft, of a dial, cast to provide an extended finger knob portion, a counterweight in said knob, means extending through the knob and the counterweight for securing the dial to the condenser shaft and means for securing the counterweight to the interior of the knob portion.

4. The radio dial comprising a finger knob portion of hollow construction, a counterweight in said dial having a shaft opening therein, means for securing the counterweight in the knob, and means securing the counterweight to a shaft.

In testimony whereof I affix my signature.

[L. S.]

LEO KNIGOFF.
